[57] **ABSTRACT**

The novel inking cartridge for tape coders disclosed includes a plastic bottle or container for ink. A felt wick-type ink pad of rectangular configuration is disposed in the container and extends through a suitable opening provided in the latter, a cap for the container opening sealing the ink pad within the container against the action of spaced coil springs in the container biasing the ink pad towards and against the cap. Opposed brackets are secured to the sides of the container which engage the cap to maintain it in position, and are adapted to mount the cartridge upon a tape coder in operative position.

INKING CARTRIDGE FOR TAPE CODER

BACKGROUND OF THE INVENTION

1. Field of the Invention

The present invention relates generally to inking devices, and more particularly to a novel inking cartridge for tape coders.

2. Description of the Prior Art

Through the years there has been much activity in the ink pad art and many patents have been issued on the broad subject matter. The present assignee is the owner of U.S. Pat. Nos. 3,186,337 and 3,227,080 for tape coders illustrating inking units. There are many other such devices, but there are disadvantages inherent in even the improved structures of the assignee's said patents. Vibration of the machines may splash ink from the ink troughs. The inking wick is easily removable and it and the reservoir can be cleaned after such action, but this operation is frequently neglected by the user with the result that the ink becomes sludged and the wick fails to feed properly. Other disadvantages reside in other available structures. There has long been the need of a device for supplying ink to the transfer or inking roll of a coder and the like, which overcomes the known disadvantages and which can be readily employed in the place of such structures.

SUMMARY OF THE INVENTION

In brief, the present novel inking cartridge for tape coders comprises a bottle or container for ink within which is disposed a wick-type ink pad biased outwardly through an opening in the container. A cap seals the ink pad within the container, being held in position by brackets which also function as supporting means for the cartridge in its attachment to a coder and the like.

Therefore, objects of the present invention are to provide a novel inking cartridge for coders and the like, which fulfills the long existing need in the art, which can be readily applied to a machine at the factory, at the office, or in the field, which is a self-contained sealed unit ready for use as a complete replacement for the existing inking device or for the same type cartridge structure, which avoids the spilling of ink both prior to and during use, which, while the container can be refilled, is inexpensive and can be discarded when empty, which can be easily and quickly applied to and removed from a coder and the like with minimum instruction, which includes a presaturated wick pad providing instant ink feeding for the transfer roll without adjustments and without time delay for capillary feeding, which provides for a quick change-over to other colors, and which otherwise fulfills the objects and advantages sought therefor.

BRIEF DESCRIPTION OF THE DRAWINGS

FIG. 1 is a front elevational view of an inking cartridge for tape coders and the like, constructed in accordance with the teachings of the present invention;

FIG. 2 is a side elevational view thereof;

FIG. 3 is a rear elevational view thereof, a portion being broken away to illustrate an attachment detail;

FIG. 4 is an enlarged vertical cross-sectional view taken on substantially the line 4-4 of FIG. 1;

FIG. 5 is a side elevational view of an ink pad forming a part of the present cartridge, a portion being broken away for conservation of space and a part being in section to show a spring well;

FIG. 6 is an enlarged fragmentary view showing a portion of the cap; and

FIG. 7 is a side elevational view showing the present novel cartridge attached to a coder in operative relation, a portion of the coder being broken away for space saving and portions of the coder die wheel support being in section for illustration of detail.

DESCRIPTION OF THE PREFERRED EMBODIMENT

Referring to the drawings more particularly by reference numerals, 8 indicates generally an inking cartridge for tape coders, and the like, incorporating the principles of the present invention. The cartridge 8 includes a bottle or container 10 of the configuration clearly shown in the drawings including an interior transverse trough 12 and a transverse neck portion 14 defining a rectangular opening 16 (FIG. 4). A rectangular felt wick-type ink pad 18 has its lower end in the trough 12 and its upper end extending into the neck portion 14 when the container 10 is closed by a cap 20 and protrudes beyond the opening 16 when the cartridge 8 is in use under the bias of coiled compression springs 22 disposed in wells 24 in the ink pad 18 (FIGS. 4 & 7). The cap 20 is of the configuration clearly shown in the drawings including an elongated base portion 26 receiving a gasket 28 of resilient neoprene or other suitable material, a vertical web 30 serving as a handle portion which can be grasped between the thumb and fingers in removing it from or returning it to the position of FIG. 4, and an enlarged integral free edge portion 32 of annular cross section terminating at each end in a camming surface 33 and having a notch 34 adjacent each end, as is clearly illustrated in FIG. 6. A bracket 36 is secured to each side of the container 10 by spaced bosses or buttons 38 formed integral with the container 10 extending through spaced holes in the brackets 36 and peened over by heat or the like to hold the brackets 36 in position. Each bracket 36 has a hook portion 40 and an arm portion 42 including a notch 44. As is clear from FIGS. 3, 4 and 6, the hook portion 40 of each bracket 36 fits into a notch 34 when the cartridge 8 is in the sealed, ready for use relationship of FIG. 4.

The inking cartridge 8 is sold and stored in the relationship of parts as shown in FIGS. 1-4. In order to ready the cartridge 8 for use on a tape coder and the like, the cap 20 is pressed down against the resilience of the gasket 28 to free the hook portion 40 of one bracket 36 from the engaged notch 34. In such position, the bracket 36 is deflected outwardly to permit the cap 20 to be raised and released from the other bracket 36 in a tilting movement. The hook portions 40 of the brackets 36 are hooked over the shaft 48 of an inking roller 50 and the notch 44 of the hook portion 40 engages the roller frame casting 52 of a coder designated generally as 54, see FIG. 7. The coder 54 also includes a die wheel assembly 56 which is in operative engagement with the ink transfer roller 50. It also includes mounting brackets 58, all of which parts are more particularly shown in the two above-mentioned patents and per se form no part of the present invention. The ink pad 18 extends beyond the neck of the opening 16 of the container 10 under the influence of the springs 22 into engagement with the ink transfer roller 50.

It is palpable from the foregoing description taken with the drawings that the cartridge 8 may be readily and quickly removed from the position of FIG. 7 and quickly recapped, and that another cartridge, as of a different color, may be as quickly readied for use and applied to the coder 54 in the position of FIG. 7.

The container 10 and cap 20 in a commercial embodiment are made of plastic materials, but any suitable material may be employed. The brackets 36 are of thin springy steel, permitting lateral movement of the hook portions 40 in capping and uncapping actions, but other suitable materials may be employed.

It is clear that there has been provided a novel inking cartridge for coders and the like which fulfills the objects and advantages sought therefor.

It is to be understood that the foregoing description and the accompanying drawing have been given by way of illustration and example. It is also to be understood that changes in form of the elements, rearrangement of parts, and substitution of equivalent elements, which will be obvious to those skilled in the arts, are contemplated as within the scope of the present invention which is limited only by the claims which follow.

What is claimed is:

1. An inking cartridge for coders and the like comprising, in combination, an ink container, a wick ink pad in and extendable from said container, removable means sealingly and positively holding said pad in said container, and means positively maintaining said removable sealing and holding means in sealing and holding position, said sealing means including a compressible sealing gasket, said maintaining means comprising a bracket at each side of said container, each bracket including a portion releasably engaging said sealing means, said compressible gasket cooperating with said engaging portion in permitting release of the latter to remove said sealing means.

2. The inking cartridge of claim 1 in which said bracket engaging portion is formed to engage also a part of a coder in mounting said cartridge thereon, each bracket also including a portion adapted to engage a coder in cooperation with said engaging portion to hold said cartridge in operative position on a coder.

3. An inking cartridge for coders and the like comprising, in combination, an ink container, a wick ink pad in and extendable from said container, removable means sealingly and positively holding said pad in said container, and means positively maintaining said removable sealing and holding means in sealing and holding position, means biasing said ink pad into engagement with said removable sealing means and into position extending from said container upon removal of said removable sealing means, said sealing means including a compressible sealing gasket, said maintaining means comprising a bracket at each side of said container, each bracket including a portion releasably engaging said sealing means, said compressible gasket cooperating with said engaging portion in permitting 30

release of the latter to remove said sealing means.

4. The inking cartridge of claim 3 in which said bracket engaging portion is formed to engage also a part of a coder in mounting said cartridge thereon, each bracket also including a portion adapted to engage a coder in cooperation with said engaging portion to hold said cartridge in operative position on a coder.

5. An inking cartridge for coders and the like comprising, in combination, an ink container, a wick ink pad in and extendable from said container, removable means sealingly and positively holding said pad in said container, and means positively maintaining said removable sealing and holding means in sealing and holding position, said sealing and holding means including a handle portion, said maintaining means including a bracket at each side of said container having a hook portion engageable with said handle portion to maintain said sealing and holding means in position.

6. The inking cartridge of claim 5 in which said handle portion includes spaced notches, each engageable bracket hook portion being in a notch when said cartridge is sealed, and means permitting depression of said sealing and holding means to allow removal of said engageable bracket portions from said notches.

7. The inking cartridge of claim 6 in which said handle portion includes camming means engageable by and facilitating return of said engageable bracket hook portions to said notches in placing said sealing and holding means on said container.
